UNITED STATES PATENT OFFICE.

FRANK NENTWICH, OF EAST LIVERPOOL, OHIO.

WINDOW.

SPECIFICATION forming part of Letters Patent No. 722,533, dated March 10, 1903.

Application filed December 4, 1902. Serial No. 133,873. (No model.)

To all whom it may concern:

Be it known that I, FRANK NENTWICH, a citizen of the United States of America, residing at East Liverpool, in the county of Columbiana and State of Ohio, have invented certain new and useful Improvements in Windows, of which the following is a specification, reference being had therein to the accompanying drawings.

This invention relates to certain new and useful improvements in windows, and has for its object to construct a window in which both the upper and the lower sash may be swung inwardly, so as to facilitate the cleaning, and also to provide novel means for locking the sash at any desired height and to dispense with the sash cords and weights as ordinarily employed in connection with windows, which are automatically held at the desired positions.

In describing the invention in detail reference is had to the accompanying drawings, forming a part of this specification, and wherein like numerals of reference indicate like parts throughout the several views, in which—

Figure 1 is a central vertical sectional view of the window constructed in accordance with my invention. Fig. 2 is a rear perspective view showing the manner in which the sash are swung inwardly to facilitate the cleaning. Fig. 3 is a front elevation of the upper sash, partly broken away to show the means for holding the same at any desired position. Fig. 4 is an elevation, partly broken away, of the lower sash, showing the means for holding the sash at any desired position. Fig. 5 is a horizontal sectional view of one of the rack-bars which are mounted in the window-frame, at one side thereof, and to which the windows are hinged. Fig. 6 is a horizontal sectional view through the frame with the sash removed.

In the accompanying drawings, illustrating my invention, 1 indicates the window-sill, 2 and 3 the respective sides of the frame, and 4 the top thereof. The frame also comprises front strips 5, rear strips 6, and intermediate strips 7, the sash sliding between the strips 5 7 and 6 7. The sash are arranged so that they may be forced laterally toward one side of the frame in order to disengage the same from between the sliding-rails at the oppo-

site side of the frame and permit of said sash being swung inwardly in order to facilitate the cleaning of the windows when desired. 55 Between the strips 5 7 and strips 6 7, adjacent to the side 2 of the frame, are arranged rack-bars 8, which are provided with a rack-face 9 and in the face, adjacent to the front of the window, are provided with a groove 60 or seat 10, placed adjacent to one edge of the rack-bar and adapted to receive the hinged rod 11. This hinged rod 11 passes through sleeves or keepers 12, carried by the lower sash 14 and also by the upper sash 15. Springs 65 17 are attached to the rear face of the rack-bars 18 and to the side 2, as seen in Fig. 1 of the drawings, and serve to hold the rack-bars pressed normally outward toward the window. At the opposite side of the frame, 70 between the strips 5 7 and strips 6 7, are arranged stationary rack-bars 18. The sleeves 12 and the rods 11 form a hinge connection between the sash-rail of one side of the sash and the vertical rack-bars 8. The frame 75 is provided at its upper end at the front portion thereof with a recess 19, closed by the bottom 20, to which is affixed the spring 21, having bowed ends which bear against the underneath face of the top 4. In order to 80 swing out the upper window 15 toward the front of the window to facilitate the cleaning, I force the lower sash 14 upwardly, the mid-rail 22 engaging the strip 20, compressing the spring 21 and allowing the upper end of 85 the sash 14 to enter the recess 19. The upper sash 15 may then be pulled downwardly until its top rail clears the lower mid-rails of the sash 14 and its lower rails clear the sill 1 of the frame, at which time the said upper sash, 90 which has now been pulled down to the lower part of the frame, may be swung inwardly in order that the window may be readily cleansed.

Means is provided for engagement with the 95 locking-bars 8 and 18 to lock the sash either in the closed or partially-opened position. This means for the upper sash 15 I have shown as comprising two locking-rods 23, the ends of which project normally beyond the 100 side walls of the sash and engage in the racks 9 of the rack-bars 8 and 18. These locking-rods operate in ways 24, provided therefor in the lower mid-rail 25 of the upper sash 15,

this mid-rail having a recess 26 therein in which is pivoted a pair of levers 27, which are connected by short links 28 to the locking-rods 23. A plate 24' is secured to the 5 sash and closes the ways 24 at the lower side. The bow-spring 29 is connected to the pivot-pins 29', which fasten the links 28 to the locking-rods 23, and thus normally hold the rods 23 in the extended position, this spring being 10 doubled as the two levers 27 are drawn toward each other. For locking the lower sash I provide the lower mid-rail 30 with inclined ways 31, through which extend the locking-rods 32, the other ends of the latter projecting normally 15 beyond the side rails of the sash and the inner ends of these rods being pivotally connected to links 33, that are in turn connected to links 34, the latter being attached at their upper ends to the pivot-pin 35, carried 20 by the thumb-piece 36, which operates vertically in back of a plate 37, which is arranged in the recess 38 in the lower sash-rail 30. It will be observed that as the thumb-piece 36 is depressed the lower ends of the 25 links or levers 34 will be spread apart, while the upper ends of the links 33 will be moved toward each other, thus retracting the locking-rods 32 out of engagement with the rack-bars 8 and 18 and permit the vertical movement 30 to be imparted to the sash 14. The locking-rods are held normally in engagement with the rack-bars by means of the bow-spring 40, which is connected to the pivoted pins which fasten the links 33 to the locking-rods 32. A suitable catch 39 is carried by the lower 35 sash-rail 30 in order to facilitate the raising of the window. It will be observed that when the thumb-piece 36 is depressed and the locking-rods 32 turned so as to be disengaged from 40 the rack-bars, the lower sash will be free to be moved up and down in the frame, as desired; also, that when the levers 27 are drawn toward each other the locking-rods 23 will be retracted and the upper sash is free to be 45 moved up and down, the sleeves 12 of both sash sliding upon the vertical hinged rod 11. When it is desired to swing the sash inwardly for the purpose of cleaning, the lower sash 14 is moved laterally, so as to depress the spring 50 17, forcing the rack-bar 8 within the frame until the opposite end of the sash is free of the slide-rails 5 and 7. The sash may then be swung inwardly on its hinge, so that ready access may be had to either side of the glass. 55 In order to swing the upper sash inwardly, the lower sash 14 is elevated until its upper end is within the recess 19, and the upper sash is then pulled downwardly and moved laterally, so as to press its locking-bar 8 in 60 order to clear the opposite side of the shaft

from between the slide-rails 6 7, and this upper sash may then be swung inwardly in the same manner as was done with the lower sash.

Having fully described my invention, what I claim as new, and desire to secure by Letters 65 Patent, is—

1. In combination with a window-frame, spring-pressed rack-bars arranged in the frame at one side thereof, a pair of sash hinged to said rack-bars, and means for locking said sash at different positions in the frame, substantially as described. 70

2. In combination with a window-frame, spring-pressed rack-bars arranged in the frame at the side thereof, stationary rack-bars arranged in the frame at the opposite side thereof, a pair of sash hinged to the spring-pressed rack-bars, and means for locking the sash at different positions, substantially as described. 75

3. In combination with a window-frame, a pair of spring-pressed rack-bars arranged in the frame at the side thereof, a pair of sash hinged to said rack-bars, and having sliding movement independent of the rack-bars, stationary rack-bars arranged in the opposite side of the window-frame, and locking means for engagement with said rack-bars to hold the sash at different positions, substantially as described. 80

4. In combination with a window-frame, a pair of spring-pressed rack-bars arranged in one side of the frame, and having grooves in one face, vertical rods mounted in said grooves, a pair of sash carrying sleeves or 95 keepers to receive said rod whereby the sash are hinged to the rack-bars to have a sliding movement independent of the bars, and means for locking the sash at different positions, substantially as described. 90

5. In combination with a window-frame having a recess at its upper end, a pair of spring-pressed rack-bars arranged in one side of the window-frame, a pair of sash hinged to the rack-bars and having a sliding movement independent of the bars, one of said sash adapted to partially enter the recess at the top of the frame when elevated, the other of said sash adapted to clear the first-named sash when lowered whereby both sash may 105 be swung inwardly, and means for locking the sash at different positions, substantially as described. 110

In testimony whereof I affix my signature in the presence of two witnesses.

FRANK NENTWICH.
